[57] CLAIM

The ornamental design for a printed-circuit board connector, as shown and described.

DESCRIPTION

FIG. 1 is a top, front and right side perspective view of a printed-circuit board connector showing my new design;

FIG. 2 is a top, rear and left side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof, the right side being a mirror image; and

FIG. 8 is a cross-sectional view thereof taken along line 8—8 of FIG. 5.
